UNITED STATES PATENT OFFICE.

SAMUEL F. ROCKWELL AND JOSEPH W. RANDALL, OF NORTH ANDOVER, MASSACHUSETTS, ASSIGNEES TO DAVIS & FURBER MACHINE COMPANY, OF NORTH ANDOVER, MASSACHUSETTS, A CORPORATION OF MASSACHUSETTS.

BUNCH-BUILDING SPINNING MULE.

Application filed February 9, 1925. Serial No. 7,787.

This invention relates to the well-known spinning mule employed for spinning various fibres, but more particularly wool fibre, and has for its object the embodiment of 5 means for building or forming a bunch or compact mass of yarn on the yarn receivers or bobbins during the winding operation, so that these yarn receivers are ready for use in an automatic filling replenishing loom 10 when removed from the mule without re-winding or other operation.

In the automatic filling replenishing looms now extensively used in the weaving of cloth, automatic mechanism is provided which acts, 15 when the yarn in running shuttle is substantially exhausted, to discharge the yarn receiver or filling carrier from the loom and substitute therefor a fresh yarn receiver or filling carrier, usually without stopping the 20 loom. Thus perfect cloth is woven without missing a pick. In order to do this, the loom is commonly provided with a feeler mechanism. In the operation of this feeler mechanism a feeler device constantly or inter- 25 mittently feels against the mass of filling on the yarn receiver or filling carrier in the running shuttle, usually at every other beat-up of the lay. When the filling has become exhausted to such an extent that only enough 30 remains to make one or more picks, a movement of the feeler is induced thereby which sets into operation the filling changing mechanism and effects replenishment. Any yarn 35 remaining upon the discharged filling carrier after replenishment is largely wasted. 40 At best it has to be removed from the filling carrier and re-spun. It is obviously desirable, therefore, that indication of substantial exhaustion by the feeler mechanism shall 45 only take place when just sufficient remains upon the filling carrier to make the necessary pick or picks required before replenishment takes place. But the ordinary filling wind placed upon the filling carrier by the spinning 50 operation is of such a character that the movement of the feeler necessary to initiate filling replenishment will not take place surely and at the same time leave the minimum requisite amount of yarn on the filling 55 carrier. To obviate this difficulty it has been common heretofore to build or form a bunch or small compact mass of yarn at the beginning of the spinning operation on the filling carrier or yarn receiver. This bunch

is of sufficient mass to effect the required 55 indicating movement of the feeler when substantial exhaustion has been reached, while at the same time it contains only enough 60 yarn to make the requisite pick or picks required before filling replenishment takes 65 place.

Heretofore no means have been provided for the building of such a bunch when yarn is spun on the mule, which is universally 70 used in spinning wool and largely used in spinning other fibres.

The object of the present invention is to provide, in connection with the spinning mule, means for forming such a bunch so that when the yarn receivers or filling 75 carriers are taken from the mule, they are ready without re-winding or other operations to be used in the automatic filling changing loom and control filling replenishment without any material wastage of yarn. 75

This and other objects of the invention will appear more fully from the accompanying description and drawings and will be particularly pointed out in the claims.

As the spinning mule in its various forms 80 is very old in the textile art and its construction and operation is familiar to those skilled in the art, and as the present invention relates to but one feature in the construction and operation of the mule, it will be necessary 85 here to illustrate and describe the construction and operation of the mule only so far as it is directly concerned with the present invention.

The drawings illustrate a well-known type 90 of spinning mule and the disclosure of preferred forms of the present invention in connection therewith will be sufficient to enable those skilled in the art to apply the principles of this invention to any type of spin- 95 ning mule.

In the drawings:

Fig. 1 is a side elevation of a portion of the central section of a spinning mule, 100 builder rail, pick motion and associated parts, the central portion being broken away and the rearward portion of the carriage and the rear frame being omitted, a preferred form of the present invention being shown in connection therewith. 105

Fig. 2 is a detail in front elevation showing a portion of the carriage and the pick motion.

Fig. 3 is a side elevation on a smaller scale showing the construction of the builder rail, supporting shoes, etc.

Fig. 4 is a top plan view on a large scale 5 of the rear portion of the construction shown in Fig. 3.

Fig. 5 is a detail in side elevation of the builder rail supporting shoe embodying a modified form of the invention.

Fig. 6 is a view similar to Fig. 5 showing a further modified form of the invention.

Fig. 7 is a view similar to Fig. 5 showing a third modified form of the invention.

In the construction illustrated there is 15 shown the usual carriage 1, which is mounted to reciprocate or slide back and forth toward and from the rear frame of the machine in a well known and familiar manner. The draft rolls 2 connected with the rear frame are 20 indicated in Fig. 1, but as the means for supporting and moving the carriage form no part of the present invention, they are not shown, nor is the rear frame of the machine shown.

25 The yarn receivers or filling carriers, one of which is shown as a bobbin 3, are mounted upon the spindles 4 rotatably mounted in the carriage. These spindles are rotated through the whorls 5 in the usual manner and 30 by any suitable means. The carriage at the front has connected thereto the brackets or standards 6 through which extend horizontally the tension faller shaft 7 and the winding faller shaft 8. One of the tension fallers 35 9, with its faller wire 10, is shown in Fig. 1. The winding fallers 11 extend from the faller shaft 8 and support at their free ends the winding faller wire 12.

In the usual operation of the mules, the 40 carriage usually moves forward with the spindles rotating in one direction or the other drawing the yarn 13 from the draft rolls 2 and putting in the twist. When the carriage reaches its front position, the spindles are usually speeded up to put a further 45 twist in the yarn, the carriage recedes as the yarn shortens with the twist, the spindles are then reversed to unwind the yarn on the tip of the spindle and then the carriage 50 moves back to effect the winding operation of the yarn thus spun on the bobbins, the spindles rotating for this purpose. The present invention is concerned entirely with the winding operation, which, as noted, takes 55 place with the carriage moving backward and with the spindles rotating. In order to lay the yarn properly on the bobbins during this winding operation, a traverse motion of the yarn with respect to the spindles must be 60 effected. This traverse motion is secured by the winding fallers 11 and the faller wire 12. The yarn leads from the draft rolls 2 over the tension faller wire 10, down under the winding faller wire 12 and thence to the bobbins 65 3. An up and down movement of the wind-

ing fallers will therefore give the required traverse motion. This traverse motion is controlled by the movement of the faller leg 14, which in the construction illustrated is a long arm made in two parts adjustably connected 70 together by the bolts 15, and which extends down toward the floor 16 at its lower end and at its upper end is pivoted at 17 to a gooseneck 18 rigidly connected to the winding faller shaft 8. It will thus be seen that 75 an up and down movement of the faller leg 14 will effect the required traverse motion.

The up and down movement of the faller leg 14 during the winding operation is secured from the builder lever 19. This lever 80 extends rearwardly and is pivoted at its rear end on the carriage in the usual manner. At its forward end it presents a guide arm 20 sliding in a vertical guideway formed by the guide block 21 bolted at 22 to the front of 85 the carriage 1. At its extreme forward end the builder lever is provided with a laterally extending square stud 23, upon which a shoulder 24 near the bottom of the faller leg 14 rests. A roller 25, journaled near 90 the forward end of the builder lever 19, rides upon the top surface of a builder rail 26. This builder rail extends fore and aft or longitudinally of the path of travel of the carriage 1. Consequently as the carriage 95 travels backwardly during the winding operation, the traverse motion of the yarn as it is wound upon the bobbins or yarn receivers will be controlled by the position of the builder rail.

Each time the carriage moves from its front position back in the winding operation, one "draw" of yarn of, say, about six feet in length is laid in a single traverse upon the bobbin or yarn receiver. When, as is the 100 case in connection with the present invention, the bobbins are wound with a filling or weft wind such as is employed in bobbins to be used in carrying the filling for weaving cloth, these traverses of yarn are laid upon the bobbins in successive superposed conical layers beginning at the bottom or base of the bobbin. Consequently the builder rail is 105 higher at the forward end than at the rearward end so that as the carriage moves backward, the faller wire 12 is traversed from the bottom upwardly a predetermined distance. Each time the carriage moves forward the builder rail must therefore be bodily lowered in order to effect the required 110 "gain" or advance of the traverse upwardly with respect to the bobbin. The mechanism employed for effecting this general operation in the type of mule illustrated is as follows.

Beneath the builder rail at the front and rear ends thereof, base plates 27 and 28 are 115 rigidly secured in longitudinal alignment to the floor 16. These base plates are provided with longitudinal guideways 29. In the base plate 28 a shoe base 30 is mounted to slide in 120

the guideways 29 and carries near each guideway rigidly connected therewith and projecting upwardly therefrom generally triangular-shaped shoes 31. In a similar manner a shoe base 32 with somewhat similar shoes 33 is mounted to slide in the ways in the base plate 27. These shoe bases are adjustably connected by a rod 34 threaded at its forward end and locked by nuts 35 in an upstanding lug 36 from the shoe base 32 and threaded at its rear end and locked by nuts 37 in an upstanding lug 38 from the shoe base 30. Consequently the two shoe bases with their shoes move together in the ways in the base plates. The builder rail at the forward end is provided with a transverse lug 39 resting upon the shoes 33 and, in the form illustrated, the builder rail is provided at the rear end with an adjusting bracket 40, having a transverse lug 41 which, during the normal winding operation, rests upon the shoes 31. This adjusting bracket is pivoted at its rear end at 42 to the builder rail, extends beneath the builder rail and is vertically adjustable thereon by means of the set screw 43.

Longitudinal movement of the builder rail with respect to the bases and the floor is prevented by a stud 44 which projects transversely through the builder rail and rides in a vertical slot 45 in a standard 46 secured to the front base 28. It will thus be seen that as the shoes 33 and 31 are shifted, the builder rail is bodily raised and lowered.

In order to effect the lowering of the builder rail at each movement of the carriage so as to shift the traverse of the yarn upwardly on the bobbins, a pick motion is provided for shifting the shoes rearwardly step by step.

The pick motion here employed is illustrated in detail in Figs. 1 and 2. A vertical standard 47, having a base plate 48, is secured by bolts 49 to the front base plate 27. A shaft 50 is rotatably mounted in the standard 47 and has a rearwardly extending threaded portion 51 threaded into a lug 52 mounted at 53 on the shoe 33. Consequently rotation of this shaft 50, which is fixed against longitudinal movement in the standard 47, will move the shoes longitudinally. This shaft 50 has rigidly secured thereto a gear 54. An elbow lever 55 is loosely fulcrumed on the shaft 51 adjacent the gear 54 and has journalled in its lower end a connected pinion 56 and ratchet wheel 57. A pawl 58 is pivoted at 59 to the upper arm of the elbow lever 55 and engages the ratchet wheel 57. The elbow lever tends to swing downwardly by reason of the weight of the pinion 56 and ratchet wheel 57 and is additionally weighted at 60 for this purpose. The downward limit of the movement of the elbow lever 55 is adjustably determined by contact of the projecting end of the pivot

stud of the pinion 56 with a stop plate 61 vertically adjustable on the vertical screw standard 62 and held in adjusted position by the nut 63. A striker lever 64 extending in a fore and aft direction is fulcrumed at 70 on a rearwardly extending projection 66 from the standard 47. This striker lever at its front end has pivoted thereto at 71 a link 68, in turn pivotally connected at its lower end at 69 to the downwardly extending arm of the elbow lever 55. A bunter arm 70 is adjustably mounted by a slot 71 and set screw 72 connection in a guideway 73 in the lower end of the guide block 21. This bunter arm carries at its forward end 80 vertically adjustable in the slot 74 a transverse stud 75 on which is mounted a roller 76. Each time the carriage comes forwardly, this roller 76, riding on the rearward end of the strike lever 64, depresses the rearward end of this lever and through the connections described rocks the elbow lever 55, bodily raising the pinion 56 and the ratchet wheel 57, but as the ratchet wheel is locked by the pawl 58, the pinion 56 is locked to the gear 54 and consequently the gear 54 is rotated, rotating the screw 51 and moving the shoes rearwardly a distance determined by the adjustments provided. 95 As the carriage moves backwardly and the striker lever 64 is released, the weighted elbow lever drops. A friction block 77 on the standard base 48 engages the gear 54 so that as the elbow lever 55 drops, the gear 54 being held against rotation, the pinion 100 56 and ratchet wheel rotate to a new position without rotating the shaft 50.

In the present invention, in order to build the required bunch, preferably at the base of the bobbin, the traverse motion between the winding faller and the spindles carrying the yarn receivers is retarded so that for a predetermined number of traverses or during the laying of a predetermined number of "draws" upon the yarn receivers the yarn is crowded into a small, compact mass. While this result may be effected within the broad scope of the invention in various ways, simple and preferred constructions are herein illustrated, as preferred embodiments of 110 the invention for doing this by giving a predetermined position to the builder rail so that during the reciprocations of the carriage which effect the preliminary traverses, the movement of the faller is retarded to 115 any required degree. The builder rail may therefore be maintained in a horizontal plane or at any required degree of inclination, or at progressive degrees of inclination, as desired, so as to effect the required retardation during the preliminary traverses. This will depend largely upon the character of the yarn being spun and the size of the bunch required. 120

In the preferred form illustrated in Figs. 130

1-4, inclusive, in the drawings, an auxiliary shoe 78 is mounted to slide vertically on guide studs 79 mounted in the rear shoe 31. This auxiliary shoe, at the beginning of the 5 winding operation, projects above the top surface of the shoe 31, and the stud 41 at the rear end of the builder rail rests thereupon instead of upon the regular shoe 31. The 10 length and shape of the top surface of this auxiliary shoe and the extent to which it projects above the surface of the regular shoe will, in connection with the surface of the front shoe 33, determine the position of the builder rail during the preliminary traverses 15 and may be arranged to effect any desired degree of retardation of the traverse. In the construction illustrated, a bell crank lever 80 is fulcrumed at 81 on the shoe 31 with its rearwardly extending arm supporting the 20 auxiliary shoe 78 and its downwardly extending arm abutting a stop plate 82 adjustably mounted by the slot 83 and set screw 84 connection on the floor base plate 28. In this form at each reciprocation of the carriage 25 as the pick motion advances the shoe 31 rearwardly, the fulcrum point 81 of the bell crank lever 80 is carried rearwardly with respect to the stop plate 82 and consequently the auxiliary shoe 78 is lowered so that the 30 extent of retardation of the traverse is accordingly decreased, and this decrease in retardation progressively continues until the auxiliary shoe is lowered to the level of the surface of the regular shoe 31 and the builder 35 rail resumes its support from the regular shoe 31, as shown in Fig. 3, when the traverse motion proceeds in the usual manner.

It will thus be seen that in this form of construction means are provided for shifting 40 the auxiliary shoe during a predetermined number of preliminary traverses, according to the requirements and as provided by the various adjustments, at each operation of the pick motion until the regular shoe resumes support of the builder rail, thus 45 crowding the yarn in a bunch on the yarn receivers at the beginning of the winding operation, and accordingly increasing the length of traverse until that normally prevailing 50 under the operation of the regular shoes is reached. In other words, means are provided for giving a relatively short traverse motion of any required extent, or in fact, no traverse at all, between the winding faller and the yarn receivers at the beginning 55 of the winding operation to crowd the yarn into a bunch at the base of the receivers and for thereafter giving a relatively long traverse motion for winding the body of the yarn on the receivers.

Other forms of auxiliary shoes which enable the main features of the invention to be secured and provide for variations in the character of the bunch are illustrated in 60 Figs. 5, 6 and 7. But it is to be understood

that the invention is broader in its scope than any of the particular constructions illustrated, wherein an auxiliary shoe is shown in connection with the rear main shoe. These disclosures are for illustrated 70 preferred forms of the invention, which is not to be restricted in its scope other than as set forth in the claims.

In Fig. 5, the auxiliary shoe comprises a suitably shaped cam block 85 secured in position by set screws 86 to the upper surface of the shoe 31. The surface of this cam block merges into the surface of the main shoe 31. The shape, size and position of the bunch is therefore determined by the 80 shape and size and position on the main shoe 31 of this cam block 85.

In Fig. 6, the auxiliary shoe 87 is in the form of a lever fulcrumed at 88 on the main shoe 31. A stop plate 89 is adjustably 85 mounted on the floor base plate 28, as in the first construction described. A spring 90 holds the lower arm of the auxiliary shoe toward the stop plate. A stud 91 limits the clockwise movement of the auxiliary 90 shoe. At the beginning with a new set of filling carriers, the parts are in the position shown in Fig. 6, so that the size, shape and position of that part of the auxiliary shoe projecting above the top surface of the main 95 shoe determines the size, shape and position of the bunch. As the winding of the set proceeds and the pick motion feeds the shoes rearwardly, the auxiliary shoe 87 swings step by step clockwise about its fulcrum 88 until its upper surface coincides with the 100 upper surface of the shoe 31.

In the construction shown in Fig. 7, the auxiliary shoe 92 is in the form of a plate adjustably mounted by the set screw 93 105 on the main shoe 31, and so shaped that different portions of its periphery may be positioned above the surface of the main shoe 31 to determine the size, shape and position of the bunch. This plate may be of 110 any desired shape and is conveniently shown as circular and as pivoted eccentrically to secure the desired results.

Having thus described the invention, what is claimed as new, and desired to be secured 115 by Letters Patent, is:

1. A spinning mule comprising a movable carriage, yarn receivers rotatably mounted thereon, means to move the carriage forwardly to draw the yarn and rearwardly to 120 wind the yarn on the yarn receivers, a faller on the carriage moveable to effect the required traverse of the yarn during the winding operation, and means temporarily to retard the traverse movement of the faller, 125 thereby to form a bunch on the yarn receiver during such retardation.

2. A spinning mule comprising a carriage, means to move the carriage forwardly during the spinning operation and rearwardly 130

- 6 during the winding operation, yarn receivers 70
rotatably mounted on the carriage, means to
wind the yarn thereon during the rearward
movement of the carriage, a winding faller
5 mounted on the carriage and movable to ef-
fect the required traverse of the yarn, and
means for giving a relatively short traverse
movement between the winding faller and the
yarn receivers at the beginning of the wind-
10 ing operation to crowd the yarn into a bunch
at the base of the receivers and for there-
after giving a relatively long traverse mo-
tion for winding the body of the yarn on
the receivers.
- 15 3. A spinning mule comprising a carriage,
means to move the carriage forwardly during
the spinning operation and rearwardly dur-
ing the winding operation, yarn receivers
20 rotatably mounted on the carriage, means
to wind the yarn thereon during the rear-
ward movement of the carriage, a winding faller
mounted on the carriage and movable
25 to effect the required traverse of the yarn,
means for giving a relative traverse motion
to the winding faller and yarn receivers, and
means for retarding the traverse motion for
30 a predetermined period during the first part
of the winding operation to cause the yarn
to form a bunch near the base of the yarn
receivers.
4. A spinning mule comprising a carriage,
means to move the carriage forwardly during
the spinning operation and rearwardly
35 during the winding operation, yarn receivers
rotatably mounted on the carriage, means to
wind the yarn thereon during the rearward
movement of the carriage, a winding faller
40 mounted on the carriage and movable to ef-
fect the required traverse of the yarn, a
builder rail extending lengthwise of the path
of movement of the carriage, and means on
45 the carriage and builder rail cooperating
during the backward movement of the car-
riage to effect a relatively short traverse
motion between the winding faller and the
50 yarn receivers at the beginning of the wind-
ing operation to crowd the yarn into a bunch
at the base of the receivers and for thereafters
giving a relatively long traverse motion for
55 winding the body of the yarn on the re-
ceivers.
5. A spinning mule comprising a carriage,
means to move the carriage forwardly during
the spinning operation and rearwardly
60 during the winding operation, yarn receivers
rotatably mounted on the carriage, means to
wind the yarn thereon during the rearward
movement of the carriage, a winding faller
65 mounted on the carriage and movable to ef-
fect the required traverse of the yarn, a
builder rail extending lengthwise of the path
of movement of the carriage and controlling
the traverse motion of the winding faller,
70 shoes supporting the ends of the builder rail
and movable to vary the position of the
builder rail, a pick motion for effecting the
movement of the shoes, and an auxiliary shoe
75 to support one end of the builder rail at the
beginning of the winding operation thereby
to effect retardation of the traverse motion
of the winding faller until a bunch is formed
on the yarn receiver, the builder rail at the
80 conclusion of the formation of the said
bunch resuming its support from the regular
shoes.
6. A spinning mule comprising the con-
struction defined in claim 5, together with
means for shifting the position of the auxil-
85 iary shoe with respect to the regular shoe at
each operation of the pick motion grad-
ually to increase the length of traverse dur-
ing the building of the bunch.
7. A spinning mule comprising the con-
struction defined in claim 5, together with
means for shifting the position of the auxil-
85 iary shoe with respect to the regular shoe at
each operation of the pick motion until the
regular shoe resumes support of the builder
rail, thus gradually increasing the length of
traverse to that effected by the regular shoes. 90
8. In a spinning mule, a builder rail,
builder shoes supporting said rail, a faller
leg controlled by said rail, faller wires con-
trolled by said leg, a supplemental shoe
95 adapted to support said rail independently
of said first named shoes, means for holding
said supplemental shoe in operative position,
and automatically operable means for with-
drawing said holding means, said automatic-
100 ly operable means being adapted to with-
draw said supporting means after a pre-
determined number of draws.
9. In a spinning mule, a builder rail,
builder shoes supporting said rail, a faller
leg controlled by said rail, faller wires con-
trolled by said leg, a supplemental shoe
105 adapted to support a portion of said rail
independently of said first named shoes, a
builder rod connected to said first named
builder shoes, and operative mechanism con-
trolled by said builder rod and operative
110 after a predetermined number of draws to
render said supplemental shoe inoperative.
10. In a spinning mule, a builder rail, a
plurality of shoes supporting said rail, a
builder rod controlling said shoes, a supple-
115 mental shoe for said rail, means for moving
said supplemental shoe to operative position
and for supporting said shoe in position to
engage and support the rail, and operative
connections between said rod and said mov-
ing and supporting means for automatically
rendering said supplemental shoe inoper-
ative after a predetermined number of draws. 120
11. In a spinning mule, a builder rail, a
shoe adapted to engage and support said rail,
means for moving said shoe to operative
position and for holding the shoe in oper-
ative position, and automatically operable
control means for rendering said shoe in- 125
130

operative after a predetermined number of draws.

12. In a spinning mule, a builder rail, a shoe adapted to engage and support said rail, means for moving said shoe to operative position and for holding the shoe in operative position, and automatically operable control means for said shoe moving and supporting means for rendering said shoe inoperative after a predetermined number of draws.

13. In a spinning mule, a builder rail, a shoe for engaging and supporting said rail, a supplemental shoe disposed side by side with said first shoe, means for moving said supplemental shoe into engagement with the rail, whereby the rail will be supported thereby, and means automatically operable after a predetermined number of draws for rendering said supplemental shoe inoperative and said first shoe operative to support the rail.

14. In a spinning mule, a builder rail, a bunch builder shoe adapted to engage and support said rail, means for moving the shoe to and supporting the shoe in operative position, and means for building a bunch of a desired size and for rendering said shoe thereafter inoperative.

15. In a mule spinning machine, a builder rail, builder shoes supporting said rail, a faller leg adapted to be supported by said rail, faller wires controlled by said leg, a supplemental shoe adapted to support said rail independently of said first named shoes, and adjustable means for holding said supplemental shoe in operative position.

16. In a mule spinning machine, a builder rail, builder shoes supporting said rail, a faller leg controlled by said rail, faller wires controlled by said leg, a supplemental shoe adapted to support said rail independently of said first named shoes, adjustable means

for holding said supplemental shoe in operative position, and automatically operable means for withdrawing said holding means.

17. In a spinning mule, a builder rail, builder shoes supporting said rail, a faller leg controlled by said rail, faller wires controlled by said leg, a supplemental shoe adapted to support said rail independently of said first named shoes, means for moving said supplemental shoe to and for retaining the shoe in operative position, and automatically operable control means for rendering said supplemental shoe moving and retaining means inoperative to support the shoe.

18. In a spinning mule, a builder rail, a bunch builder shoe adapted to engage and support said rail, means for moving the shoe to and supporting the shoe in operative position, a lever actuated at each draw and means controlled by said lever for automatically rendering said bunch builder shoe inoperative after a predetermined number of draws.

19. In a spinning mule, a builder rail, means to engage and support said rail in an abnormal position in which said rail is effective to cause a bunch to be wound on a bobbin or cop in said mule, and automatically operated means effective to restore said rail to normal running position after a predetermined number of draws.

20. In a spinning mule, a builder rail, a member effective in one position to engage and support said rail in bunch building position, and mechanical means to move said member from such position after a desired bunch is wound and to thereby restore said builder rail to normal running position.

In testimony whereof, we have signed our names to this specification.

SAMUEL F. ROCKWELL.
JOSEPH W. RANDALL.
